DESIGN FOR A COMBINED PAPER HOLDER AND NOTEBOOK SUPPORT

George B. McCay and Warren E. Hacker,
Shaker Heights, Ohio

Application March 25, 1948, Serial No. 145,334

Term of patent 14 years

(Cl. D74—1)

To all whom it may concern:

Be it known that we, George B. McCay and Warren E. Hacker, citizens of the United States and residents of Shaker Heights, in the county of Cuyahoga and State of Ohio, have invented a new, original, and ornamental Design for a Combined Paper Holder and Notebook Support, of which the following is a specification, reference being had to the accompanying drawings, forming a part thereof.

In said drawings,

Fig. 1 is a front perspective view of a combined paper holder and notebook support showing our new design;

Fig. 2 is a side elevational view thereof; and

Fig. 3 is a top plan view thereof.

In all views, the dominant feature of our design is shown in full lines.

We claim:

The ornamental design for a combined paper holder and notebook support, substantially as shown and described.

GEORGE B. McCAY.
WARREN E. HACKER.
